(57) **CLAIM**

The ornamental design of a low-profile bedpan, as shown and described.

DESCRIPTION

FIG. 1 is a perspective view of a low-profile bedpan configured in accordance with the present invention;

FIG. 2 is a top view of the low-profile bedpan;

FIG. 3 is a bottom view of the low-profile bedpan;

FIG. 4 is a right side view of the low-profile bedpan;

FIG. 5 is a left side view of the low-profile bedpan;

FIG. 6 is a front view of the low-profile bedpan; and,

FIG. 7 is a back view of the low-profile bedpan.

The broken lines in the drawing are included for the purpose of illustration and form no part of the claimed design.

1 Claim, 4 Drawing Sheets(56)
